UNITED STATES PATENT OFFICE

CARL WILHELM HARTMANN, OF LYNGBY, NEAR COPENHAGEN, DENMARK

MEANS FOR PRODUCING LINED CARTONS

Application filed April 25, 1931, Serial No. 532,872, and in Great Britain April 29, 1930.

This invention relates to machinery whereby cardboard or other like cartons can be folded from blanks and have applied to them a lining, for instance a paper or sheet cellulose material lining adapted to be folded in with the flaps of the carton and pasted or glued to produce a sealed carton.

The object of the present invention is to provide a machine which will mechanically adhere the lining to the cardboard or like blanks, the adhesion being effected along the required lines appropriate to the folds of the carton blanks.

Broadly my invention is characterized in that means is provided for feeding a carton blank simultaneously with a sheet of paper or other suitable lining material on to a moving surface having means adapted to apply suction to the lining on predetermined lines or points and by such suction to hold the sheet in correct register with the blank for adhesion one to the other, the said surface by its movement delivering the registering sheet and carton therefrom, means being provided for applying an adhesive to the sheet or carton on substantially such predetermined lines or points before the sheet and blank are brought into registration and means for pressing them together during or subsequent to such registration.

The said moving surface is preferably a hollow cylinder connected internally to a source of suction and formed on its periphery with a large number of small holes so that a sheet contacting with the cylinder is drawn by the suction closely against the surface of the cylinder. This suction can be utilized to hold the sheets in the correct position on the cylinder to ensure that the lining paper and carton blank will be secured together in the correct relative positions. A series of holes are provided in the cylinder each adapted to be closed or left open. By closing some of the holes in the cylinder, the unclosed holes may be selected so that they form a series of holes arranged on lines corresponding to the outline of the lining sheets or the points at which the sheets and cartons are to be adhered to each other.

The paper or other suitable material is

preferably supplied from a roll and is drawn from the roll by suitable drawing rollers adapted to convey the paper past a device for cutting or punching it to the predetermined outline, the paper being subsequently drawn by a pair of rotating gripping rollers the distance corresponding to one dimension of the lining appropriate to one carton. At the completion of the drawing action the paper is partially wrapped round the said cylinder and severed by a knife the continued rotation of the cylinder carrying the severed strip of paper into contact with a cardboard or like carton blank fed simultaneously from a supply stack. The carton blanks can be selectively removed from the supply stack by a suction and gripper device which delivers each such blank on to a conveyor which carries the blank over a pasting roller, the surface of such roller being shaped so as to apply the paste to the blank on the outline it is required to adhere the lining to it.

In order that my invention may be clearly understood and readily carried into effect I have appended hereto 2 sheets of drawings illustrating an embodiment thereof and wherein:

Fig. 1 is a diagrammatic side elevation view showing the sequence of operations and the important elements of my invention.

Fig. 2 is a side elevation showing the working parts of the machine.

Fig. 3 is a part sectional side elevation view of the rotary suction cylinder.

Fig. 4 is a fragmentary view of Fig. 5 looking in direction of arrow X to show the arrangement of the suction holes in the cylinder.

Fig. 5 is a section on the line B—B of Fig. 3.

Fig. 6 is a detail broken view showing the lining side of a lined carton in which the cross section of the carton when folded is square, and

Fig. 7 is a similar view but in which the cross section of the folded carton is oblong.

Referring first to Figs. 6 and 7 of the accompanying drawings an idea is formed as to the construction of the cardboard or the like blanks and the lining pasted thereto. In Fig. 6 each end of the cardboard blank A is

formed with two symmetrical square flaps B adapted to close the ends of the carton, the lining C being formed with substantially half hexagonal recesses C¹ and being shorter than the maximum length of the carton blank from top to bottom. In Fig. 7 this latter dimension of the cardboard blank and lining are equal.

In Fig. 1 is shown diagrammatically how 10 a stack of cardboard blanks A stacked on an inclined platform 1, and a roll 2 of paper or other suitable sheet material adapted to supply the lining blanks are fed from different ends of a machine having pasting and shaping devices to a common rotary cylinder 3 where the cardboard blanks and linings are superimposed in proper registration for being pressed together on predetermined lines and fed ready for folding into boxes on to a receiving platform 4, the stack of finished lined blanks being indicated by the reference numeral A².

The cylinder 3 has intermittent rotary motion imparted to it, and it serves as a means 25 of picking up each cut off length of lining and conveying it through a semi-circular path from a lining cutting device 5 to which the desired length of lining is fed by a pair of rollers 6 and 7 between which the paper is 30 gripped and drawn over an idle roller 8. The rollers 6 and 7 grip the paper and they rotate to feed the paper between them towards the cylinder 3. The severed length of paper to constitute the lining is held close against the 35 cylinder 3 by suction, the interior of the cylinder being connected to a source of suction and multitudinous holes being formed in the periphery of the cylinder.

Simultaneously with the feeding of the 40 predetermined length of lining on to the cylinder 3 a cardboard or other suitable blank is fed on to guiding rails 9 from the stack A and conveyed over a pasting roller 10 so that it becomes pasted to a predetermined outline 45 by appropriately shaping the periphery of the pasting roller 10 and is then delivered on to the cylinder 3 so that its leading edge meets the leading edge of the lining being conveyed with the cylinder 3, a roller 11 lightly contacting with the periphery of the said cylinder initially pressing the cardboard blank and lining and guiding them between a pair of pressing rollers 12 and 13 on to the receiving platform 4.

50 In order to ensure correct registration of each lining blank with the cutters 5 at the proper movement, adjustment can be effected by applying a pull to the paper or slackening it at a point in advance of the feed rollers 6 and 7. This can be effected by passing the paper over a pair of idle rollers 14 and 14a which are located so as to put a loop in the paper, the position of the roller 14 being adjustable by hand. The paper is drawn from 55 the supply roll by a pair of drawing rollers 15

and 16 and is thereafter drawn by the rollers 6 and 7 over a pair of idle rollers 17 and 18 located relative to each other so as to put a small loop in the paper enabling the paper to be drawn taut by reason of the friction of the rollers 17 and 18 opposing the movement of the paper over the roller 14a. Between the rollers 14a and 17 is located a punch or die 19 over the bed of which the paper is drawn, and between the drawing movement of the rollers 6 and 7 the paper is cut by the punch 19 forming openings of the required outline, the cutters 5 finally severing the paper along the middle of these openings cutting the paper lining to the correct outline and length. The device for pushing the carton blanks along the guides 9 is diagrammatically indicated by the reference numeral 21.

Referring now to Fig. 2 this shows the arrangement of the parts of the machine relevant to the present invention, and I shall only refer to the important parts as it is obvious that most of the mechanical movements shown have a number of alternative equivalent forms. The cylinder 3 is formed with a gear wheel 3a with which meshes a quadrant 22 of much larger radius than the cylinder 3, this quadrant 22 being connected by a rod 23 to a wheel 24 continuously rotating in the direction of the arrow. The radius of the quadrant 22 is greater than that of the wheel 24 and consequently the quadrant 22 is oscillated. The edge of the lowermost cardboard blank A is drawn down by a suction device and grippers on the conveyor device grip the blank so that movement of the conveyor will withdraw the lowermost cardboard blank from the stack. The cardboard blank is moved along the guide 9 by the conveying device as previously referred to and it is delivered on to the cylinder 3 so that its leading edge meets the leading edge of the lining carried round the cylinder. The conveyor consists of a carriage with rack, getting reciprocating movement from the quadrant 22 by means of the wheel 24 over the wheel 26. The cylinder 3 is moved direct by the quadrant 22, and by the wheel 26 the movement unisonously with the working stroke is transferred to the pasting cylinder 10. When the carriage after having guided the cardboard blank to the cylinder returns in order to collect a new blank, provisions have been made to the effect that the cylinders 3 and roller 10 are standing still and consequently also the conveying organs at 6 and 7 mentioned below. The cardboard blank can be pressed downwards against the cylinder 3 by the roller 11 which is supported in a slotted arm 11a.

The feeding rollers 6 and 7 can be adjusted longitudinally to suit different lengths of lining and the method of adjustment can comprise a hand wheel 27 formed with a worm 28 meshing with a worm wheel 29 on a feed screw 100

30 adapted to adjust lengthwise a bracket 32 carrying a splined shaft 31 from which the rollers 6 and 7 are driven by a bevel wheel 33 meshing with a train of gear wheels 34 driven from a gear wheel 35 on the shaft of the cylinder 3.

To adjust the said train of gear wheels to changes in position of the bracket 32 one of the gear wheels 34 is mounted for adjustment along an arcuate guide 34a.

The roller 14 for registering the lining material at the appropriate moments with the cutter 5 is adjustable so as to enable the length of the loop formed in the paper P to be adjusted and a suitable fine adjustment can be effected readily by a handle 36 adapted to rotate a worm spindle 36a meshing with a segmental worm wheel 36b mounted on a spindle 37 to which is fixed radially an arm 38 carrying at its free end the roller 14. The segmental worm wheel 36b is formed with a diametrically opposite integral segmental part 36c slotted arcuately to receive a bolt 39 for holding it in selected position.

25 The device 19 for shaping the lining blanks can be operated from links and levers indicated at 40 which are connected by a rod 41 to a suitable part of the machine synchronized with the rotation of the cylinder 3.

50 Referring to Figs. 3, 4 and 5 the cylinder 3 is formed with a number of parallel or otherwise suitably disposed circumferential grooves or channels 42. Rows of narrowly spaced holes 43 are arranged communicating with suction passages within the cylinder and each hole is provided with a plug so that selected holes may be left open following a line corresponding approximately to the outline of the edge of the lining. This cylinder is divided into two diametrically opposite symmetrical hollow part annular section chambers 44 to which suction is applied successively to effect the desired suction for each such hollow suction part of the cylinder to pick up a lining blank fed from the rollers 6 and 7 and to carry it round to meet the cardboard blank. Suction is applied from a suitable source through a pair of radial conduits 45 communicating successively with a suction port in a stationary annular section body 46 mounted about the shaft 47 carrying the cylinder 3. A conduit 46a connects the interior of the body 46 to a suction passage 48 surrounding the shaft 47 and integral with the body 46, the connection to the source of suction being indicated at 49. Suitable packing for sealing the bearing faces of the cylinder 3 and the body 46 is indicated at 50.

55 The cutters 5 for severing the lining blanks can be operated from a bell crank lever such as for instance 51 fulcrumed at 52 in a block 53 and connected by a link and lever 54 and 55 respectively to a rod 56 pivot- ed to one end of a lever 57 oscillated from a driving wheel 24. A spring loaded depend-

ing arm 63 of a bell crank lever 64 is moved at the appropriate moments to operate means for feeding each blank along the guide 9, this lever 64 and another lever 65 for operating a suction device for drawing down each 70 carton blank being operated from vertical reciprocating rods 64a and 65a respectively connected respectively to the free ends of oscillating pivoted arms 64b and 65b. Between the rollers 6 and 7 and the cylinder 3, the conveyed end of a blank is carried by tapes, which are placed in an adequate manner and moved in unison with the movement of the cylinder 3 and are stationary during 75 part of the stroke.

80 By means of my invention a reliable method is provided for picking up lining blanks and conveying them on to the cardboard blanks, and the provision of the multitudinous suction holes 43 enables suction to be applied to the lining sheets on the lines corresponding to the shape of the edge of the said lining sheets.

I claim:

1. In apparatus for producing lined car- 90 tons, a moving surface and means for feeding a carton blank simultaneously with a sheet of lining material on to said moving surface, means with said moving surface adapted to apply suction to the lining, the said sur- 95 face by its movement delivering the register- 100 ing sheet and carton therefrom, means for applying an adhesive to one of the said two carton members on predetermined lines before they are brought into registration and means for pressing them together.

2. In apparatus for producing lined car- 105 tons, a moving surface and means for feeding a carton blank simultaneously with a sheet of lining material on to said moving surface, means with said moving surface adapted to apply suction to the lining, the said surface by its movement delivering the register- 110 ing sheet and carton therefrom, means for applying an adhesive to one of the said two carton members on predetermined lines before they are brought into registration and means for pressing them together, a device for feeding lining blanks on to said moving surface, said moving surface being brought successively 115 opposite the said device for feeding lining blanks so as to pick up the said lining blanks by suction and to carry the said blanks to a delivery point for receiving the carton blanks.

3. Apparatus for producing lined cartons comprising a rotating cylinder, a suction chamber in the cylinder connected to a source of suction, apertures provided in the cylinder wall communicating with said suction chamber, means for feeding carton blanks and lining sheets on to the periphery of said cylinder, means for applying adhesive on predetermined lines to one of the said carton elements, means whereby suction in said 125

chamber shall be applied at predetermined points to said carton elements, and means for delivering the blanks and linings from the cylinder.

5. In apparatus for producing lined cartons, a moving surface and means for feeding a carton blank simultaneously with a sheet of lining material on to said moving surface, means with said moving surface adapted to apply suction to the lining, the said surface by its movement delivering the registering sheet and carton therefrom, means for applying an adhesive to one of the said carton members on predetermined lines before they are brought into registration and means for pressing them together, a large number of suction apertures in said surface, and means for selectively closing said apertures whereby suction is applied to the lining on predetermined lines.

10. In apparatus for producing lined cartons, a moving surface and means for feeding a carton blank simultaneously with a sheet of lining material on to said moving surface, means with said moving surface adapted to apply suction to the lining, the said surface by its movement delivering the registering sheet and carton therefrom, means for applying an adhesive to one of the said two carton members on predetermined lines before they are brought into registration and means for pressing them together, a device for feeding lining blanks on to said moving surface, said moving surface being brought successively opposite the said device for feeding lining blanks so as to pick up the said lining blanks by suction and to carry the said blanks to a delivery point for receiving the carton blanks, a large number of suction apertures in said surface, and means for selectively closing said apertures whereby suction is applied to the lining on predetermined lines.

15. Apparatus for producing lined cartons comprising a rotating cylinder, a suction chamber in the cylinder connected to a source of suction, apertures provided in the cylinder wall communicating with said suction chamber, means for feeding carton blanks and lining sheets on to the periphery of said cylinder, means for applying adhesive on predetermined lines to one of the said carton elements, means whereby suction in said chamber shall be applied at predetermined points to said carton elements, and means for delivering the blanks and linings from the cylinder, a large number of said apertures being distributed over the surface of the cylinder, and means for selectively closing said apertures whereby suction is applied through the cylinder on predetermined lines.

20. Apparatus for producing lined cartons comprising a rotating cylinder, a suction chamber in the cylinder connected to a source

of suction, apertures provided in the cylinder wall communicating with said suction chamber, means for feeding carton blanks and lining sheets on to the periphery of said cylinder, means for applying adhesive on predetermined lines to one of the said carton elements, means whereby suction in said chamber shall be applied at predetermined points to said carton elements, and means for delivering the blanks and linings from the cylinder, two longitudinal segmental parts with said cylinder, each said part being formed with its own suction chamber and ports connecting said suction chambers successively to the source of suction.

25. Apparatus for producing lined cartons comprising a rotating cylinder, a suction chamber in the cylinder connected to a source of suction, apertures provided in the cylinder wall communicating with said suction chamber, means for feeding carton blanks and lining sheets on to the periphery of said cylinder, means for applying adhesive on predetermined lines to one of the said carton elements, means whereby suction in said chamber shall be applied at predetermined points to said carton elements, and means for delivering the blanks and linings from the cylinder, two longitudinal segmental parts with said cylinder, each said part being formed with its own suction chamber and ports connecting said suction chambers successively to the source of suction, a large number of said apertures being distributed over the surface of the cylinder and means for selectively closing said apertures whereby suction is applied through the cylinder on predetermined lines.

30. In apparatus for producing lined cartons, a moving surface and means for feeding a carton blank simultaneously with a sheet of lining material on to said moving surface, means with said moving surface adapted to apply suction to the lining, the said surface by its movement delivering the registering sheet and carton therefrom, means for applying an adhesive to one of the said two carton members on predetermined lines before they are brought into registration and means for pressing them together, a device for feeding lining blanks on to said moving surface, said moving surface being brought successively opposite the said device for feeding lining blanks so as to pick up the said lining blanks by suction and to carry the said blanks to a delivery point for receiving the carton blanks, a large number of suction apertures in said surface, and means for selectively closing said apertures whereby suction is applied to the lining on predetermined lines, a pasting roller over which the carton blanks are fed to said moving surface, the said pasting roller being shaped to apply paste to the carton blanks on the lines on which the lining blanks are adapted to be adhered to the carton blanks.

10. Apparatus for producing lined cartons comprising a rotating cylinder, a suction chamber in the cylinder connected to a source of suction, apertures provided in the cylinder wall communicating with said suction chamber, means for feeding carton blanks and lining sheets on to the periphery of said cylinder, means for applying adhesive on predetermined lines to one of the said carton elements, means whereby suction in said chamber shall be applied at predetermined points to said carton elements, and means for delivering the blanks and linings from the cylinder, and means for varying the length of lining blank sheet material to be fed on to said cylinder at each operation. 70
11. Apparatus for producing lined cartons comprising a rotating cylinder, a suction chamber in the cylinder connected to a source of suction, apertures provided in the cylinder wall communicating with said suction chamber, means for feeding carton blanks and lining sheets on to the periphery of said cylinder, means for applying adhesive on predetermined lines to one of the said carton elements, means whereby suction in said chamber shall be applied at predetermined points to said carton elements, and means for delivering the blanks and linings from the cylinder, and means for varying the length of lining blank sheet material to be fed on to said cylinder at each operation. 75
12. In apparatus for producing lined cartons, a moving surface and means for feeding a carton blank simultaneously with a sheet of lining material on to said moving surface, means with said moving surface adapted to apply suction to the lining, the said surface by its movement delivering the registering sheet and carton therefrom, means for applying an adhesive to one of the said two carton members on predetermined lines before they are brought into registration and means for pressing them together, a device for feeding lining blanks on to said moving surface, said moving surface being brought successively opposite the said device for feeding lining blanks so as to pick up the said lining blanks by suction and to carry the said blanks to a delivery point for receiving the 80 carton blanks, a large number of suction apertures in said surface, and means for selectively closing said apertures whereby suction is applied to the lining on predetermined lines, a pasting roller over which the carton blanks are fed to said moving surface, the said pasting roller being shaped to apply paste to the carton blanks on the lines on which the lining blanks are adapted to be adhered to the carton blanks, and a roller 85 over which the lining material is passed, said roller being located so as to place a loop in the path of travel of the lining material, and being translatable adjustable for adjusting the position of the lining material at its delivery end relative to the said cylinder in order to obtain correct registration of the lining and carton blanks. 90
13. In apparatus for producing lined cartons, a moving surface and means for feeding a carton blank simultaneously with a sheet of lining material on to said moving surface, means with said moving surface adapted to apply suction to the lining, the said surface by its movement delivering the registering sheet and carton therefrom, means for applying an adhesive to one of the said two carton members on predetermined lines before they are brought into registration and means for pressing them together, a device for feeding lining blanks on to said moving surface, said moving surface being brought successively opposite the said device for feeding lining blanks so as to pick up the said lining blanks by suction and to carry the said blanks to a delivery point for receiving the carton blanks, and a pair of feeding rollers adjustable translatable towards and away from the said moving surface by a screw feed device for varying the length of lining blank sheet to be fed on to said surface. 95
14. In apparatus for producing lined cartons, a moving surface and means for feeding a carton blank simultaneously with a sheet of lining material on to said moving surface, means with said moving surface adapted to apply suction to the lining, the said surface by its movement delivering the registering sheet and carton therefrom, means for applying an adhesive to one of the said two carton members on predetermined lines before they are brought into registration and means for pressing them together, a device for feeding lining blanks on to said moving surface, said moving surface being brought successively opposite the said device for feeding lining blanks so as to pick up the said lining blanks by suction and to carry the said blanks to a delivery point for receiving the 100 carton blanks, a large number of suction apertures in said surface, and means for selectively closing said apertures whereby suction is applied to the lining on predetermined lines, a pasting roller over which the carton blanks are fed to said moving surface, the said pasting roller being shaped to apply paste to the carton blanks on the lines on which the lining blanks are adapted to be adhered to the carton blanks, and a roller 105 over which the lining material is passed, said roller being located so as to place a loop in the path of travel of the lining material, and being translatable adjustable for adjusting the position of the lining material at its delivery end relative to the said cylinder in order to obtain correct registration of the lining and carton blanks. 110
15. Apparatus for producing lined cartons comprising a rotary cylinder divided longitudinally into two parts, a source of suction to the interior of both of said parts, suction holes in the working surfaces of said two parts adapted to be selectively opened and closed, a support for a stack of carton blanks on one side of said cylinder, and a rotary support for a roll of lining material on the other side of said cylinder, means for feeding the carton blanks successively from the stack to the upper side of said cylinder, and 115
16. Apparatus for producing lined cartons comprising a rotary cylinder divided longitudinally into two parts, a source of suction to the interior of both of said parts, suction holes in the working surfaces of said two parts adapted to be selectively opened and closed, a support for a stack of carton blanks on one side of said cylinder, and a rotary support for a roll of lining material on the other side of said cylinder, means for feeding the carton blanks successively from the stack to the upper side of said cylinder, and 120
17. Apparatus for producing lined cartons comprising a rotary cylinder divided longitudinally into two parts, a source of suction to the interior of both of said parts, suction holes in the working surfaces of said two parts adapted to be selectively opened and closed, a support for a stack of carton blanks on one side of said cylinder, and a rotary support for a roll of lining material on the other side of said cylinder, means for feeding the carton blanks successively from the stack to the upper side of said cylinder, and 125
18. Apparatus for producing lined cartons comprising a rotary cylinder divided longitudinally into two parts, a source of suction to the interior of both of said parts, suction holes in the working surfaces of said two parts adapted to be selectively opened and closed, a support for a stack of carton blanks on one side of said cylinder, and a rotary support for a roll of lining material on the other side of said cylinder, means for feeding the carton blanks successively from the stack to the upper side of said cylinder, and 130

means for drawing from the roll of lining material predetermined lengths of lining material and feeding them successively to the lower side of said cylinder, the suction in said cylinder picking up the lining blanks successively and conveying them to and laying them in predetermined registration with the carton blanks, and means for subsequently pressing the individual carton and lining blanks together and delivering them on to a collecting device.
